TRAIN CONTROL SYSTEM

Application filed March 7, 1929. Serial No. 345,132.

Our invention relates to train control systems in which instrumentalities on a train respond to currents in wayside circuits to cause cab signal indications and, under certain circumstances, to cause an automatic train stop operation. More particularly the invention relates to a combined brake application and cut-off valve which serves as the direct means of controlling the functions involved in automatically applying the train brakes.

The object of the invention is to provide, in apparatus of the above type, means for preventing the engineman from defeating an automatic train stop operation. To accomplish this object the equipment supplied on the train includes means for automatically applying the brakes after a certain cab signal indication is given; means for cutting off an air supply to cause the operation of electrical devices now in general use; and means for cutting off all supply of compressed air to the brake valve, thus preventing the engineman from releasing the brakes and so defeating an automatic train stop application by any movement of the brake valve or double heading cock. The above-mentioned means are incorporated in a combined brake application and cut-off valve, which forms the subject of the present invention and which can be installed in connection with the present standard brake equipment and with any of the train stop systems now in use without necessitating the use of additional apparatus such as reservoirs, equalizing pistons and the like.

Other objects and advantages of our invention will be apparent from the detailed description which follows and which has reference to the accompanying drawings, in which there is shown one embodiment of the invention. Of the drawings:

Fig. I is a diagrammatic view showing the combined brake application and cut-off valve, in connection with a part of the apparatus on the train comprising the train control system;

Fig. II is a diagrammatic view showing the remainder of the apparatus of the train control system, including such parts of stand-

ard air brake equipment as it is necessary to describe for the proper understanding of our invention;

Fig. III is an enlarged view of the combined application and cut-off valve of Fig. I, showing the same in its normal position; and,

Fig. IV is a similar view except that the application and cut-off valve is shown with its slide valve in the position which it occupies after an automatic train stop has been initiated.

The various pipe lines shown at the top of Fig. I connect with a similar number of pipe lines shown at the left hand margin of Fig. II.

The equipment comprises generally an automatic brake valve, comprehensively designated by the numeral 1, a combined brake application and cut-off valve 2, a combined magnet and application control valve 3, an independent brake valve 4 and a distributing valve 5, similarly designated. In Figs. I, II and III the apparatus is shown in its normal "running" position, in which case there is no interference with the normal function of each part.

In Fig. I there is diagrammatically illustrated a part of the electrical apparatus comprising the receiving equipment on the train which is responsive to the wayside transmitting equipment. The receiving equipment is of a type now in general use and serves to provide a continuous cab signal indication to the engineman informing him of traffic conditions in advance. This equipment also interlocks with the pneumatic equipment to initiate a brake application should the engineman fail to acknowledge a change to a more restrictive signal indication. For this purpose, a pneumatic circuit controller 6 and the combined magnet and application control valve 3 are employed. There is also provided an acknowledgment switch 7 by which the engineman may forestall an automatic train stop, and a reset switch 8, preferably located beneath the cab so as to require the engineman to descend to the ground to release the brakes. The electrical equipment is shown in the

normal running position with a clear cab signal.

The engineman may, in this system, apply the brakes through either the automatic 5 brake valve 1 or the independent brake valve 4 at any time and to any degree permissible in usual air brake practice. Application of the train brakes is effected by reducing the air pressure in the brake pipe 9, accomplished, as usual, through the medium of the 10 automatic brake valve 1 by moving the handle to the service or emergency position. Main reservoir pressure supplies air via pipe 13 and port 16 to a chamber G in the application and cut-off valve 2, thence through 15 pipe 20 and a feed valve 22 to the chamber of the rotary valve 23 of the automatic brake valve 1. The air passes through a port 24 in the bottom rotary valve seat and a port 18 20 to a double heading cock 26 and thence to the brake pipe 9. Manual "service" or "emergency" application is accomplished in the usual manner by reducing the brake pipe pressure gradually for "service" application 25 and rapidly for "emergency" application.

When a train stop operation occurs, on account of the engineman's failing to acknowledge a change to a more restrictive indication, the magnet valve 3 becomes de-energized and vents the timing reservoir 31 to atmosphere at 48 and through a restricted port 32 to the warning whistle 33 which sounds continuously for several seconds. The port 32 is so proportioned that at the 30 end of approximately six seconds, the piston 47 and upper timing valve 34 will move downward by means of the pressure exerted by the spring 35. This movement of the timing valve connects chamber 29 to atmosphere, and hence likewise connects a chamber K of the brake application valve 2 to atmosphere through pipe 10.

Normally, the main reservoir pressure on both sides of the brake application valve piston 36 is in equilibrium. When, however, pipe 10 is vented to atmosphere by the train stop apparatus, the pressure in chamber K is reduced below that in chamber H causing the piston 36 to move downward until the 45 cut-off valve 37 strikes its seat, thus preventing any flow of air from the main reservoir through pipe 13 to pipe 59 and thence to pipe 20, and thus preventing any further supply of air to the automatic brake valve 1. At the 50 same time cavity E of the slide valve 38 connects port 39 to port 15, the latter port being connected to the usual holding pipe 40 of the automatic brake valve 1, thus establishing a direct vent of pipe 10 and chamber K as 55 long as the brake valve is left in running position. The movement of the slide valve 38 also by means of cavity C connects port 11 to atmosphere through port 46, thus establishing through pipe 41 a vent of the brake 60 pipe 9, should the engineman attempt to de-

feat a train stop application by closing the double heading cock 26. The movement of the slide valve 38 also by means of cavity B connects port 12 with port 14, which connects the equalizing reservoir 28 to the reduction limiting reservoir 43. The reduction limiting reservoir is of such volume relation to the equalizing reservoir 28 that a predetermined reduction is made in the equalizing reservoir 28 and in the chamber above the 70 equalizing piston 27, causing the piston of the automatic brake valve 1 to rise and unseat its valve 59, allowing brake pipe air to flow to the atmosphere at 60. Port 61 being restricted, the pressure in the equalizing reservoir 28 and 75 the chamber above the equalizing piston 27 falls gradually. The movement of the slide valve 38 also connects pipe 42 through port 25, cavity A, and port 45 to atmosphere, and thus 80 brake pipe pressure is removed from the pneumatic circuit controller 6 and atmospheric pressure substituted therefor. This 85 operates the circuit controller 6 in such manner as to open the circuit to the acknowledging switch 7 so that the magnet valve 30 can 90 only be re-energized by operating the reset switch 8. Accordingly the brake may not be released by acknowledgment following an 95 automatic train stop application.

It will thus be seen that when the combined application and cut-off valve is moved to the position shown in Fig. IV the following operations take place:

1. There is established a direct vent of chamber K to the atmosphere which condition continues until the automatic brake valve is moved from running position to lap position.

2. There is established a vent of brake pipe 9 to the atmosphere which condition continues regardless of the position of the double heading cock 26.

3. The equalizing reservoir 28 is connected to the reduction limiting reservoir 43.

4. All supply of air from the main reservoir to the automatic brake valve 1 is cut-off.

5. A direct vent of the pneumatic circuit controller 6 is established until the brake application valve 2 is returned to normal position.

To reset the train stop apparatus, the automatic brake valve 1 must first be placed in lap position to close the atmosphere vent of pipe 40 through port 44 in the brake valve. Then when the train stops, the engineman descends to the ground and operates the reset switch 8. This re-energizes the magnet valve 30 and closes the remaining vent of pipe 10 to atmosphere. Upon moving the brake valve 1 from running position to lap position and closing pipe 40, pressure in the chamber K will become equal to that in chamber H and allow the spring 49 to force the piston 36 and slide valve 38 to normal position thus 120 125 130

venting the reduction limiting reservoir air 43 through cavity C and supplying air to pipe 42 through port 25 and cavity A and closing the circuit to the acknowledging 5 switch 7.

In Fig. II of the drawings there is shown the usual compressor governor 50 in the pipe 51 leading from the compressor. The pipe 13 leading from the main reservoir at 52 has 10 a branch connection 53 through a reducing valve 54 to the independent brake valve 4. An application cylinder pipe 55 leads from the independent brake valve 4 to the automatic brake valve 1. An additional pipe 56 15 connects the distributing valve 5 through the independent brake valve 4 with the holding pipe 40 of the automatic brake valve 1. Connections to the driver brake cylinders and tender cylinders are shown at 57 and 58, respectively. The apparatus of Fig. II comprises well known equipment which is merely illustrated to show the complete pneumatic system with which the brake application 20 valve 2 operates.

25 It will be apparent from the description that the novel construction and arrangement of the brake application valve, together with its various connections to other apparatus of the train control system produces an effective 30 safeguard preventing the engineman, once a train stop operation has been initiated, from defeating the operation by any movement other than the operation of the reset switch which first necessitates a complete train stop.

35 The combined brake application and cut-off valve 2 may be installed in connection with standard brake equipment now in use, and, though simple in construction, it serves as the direct means of controlling all the pneumatic 40 functions involved in automatic brake application and necessitates no additional reservoirs or other apparatus. It may be conveniently located contiguous to the automatic brake valve, so that the pipe connections 45 to the brake valve may be of minimum length or entirely eliminated.

While we have described the invention with some particularity, it is to be understood that the form and type of the various valves 50 and other apparatus shown may be varied without departing from the spirit of our invention, which contemplates any train control system within the definition of the claims here appended.

55 Having thus described our invention, we claim:

1. In a train control system, a brake valve, a brake pipe, a double heading cock interposed between said brake pipe and brake valve, and 60 electro-pneumatic means responsive to wayside currents for automatically operating the equalizing piston of said brake valve to effect an automatic train stop, said means including a brake application valve associated with 65 said brake valve and having means for cutting

off all supply of air to said brake valve upon an automatic train stop operation and having means for venting the brake pipe if an attempt is made to defeat a train stop operation by closing said double heading cock. 70

2. In a train control system, a brake valve, a brake pipe, a double heading cock in said brake pipe, and electro-pneumatic means responsive to wayside signals for automatically operating the equalizing piston of said brake valve to effect an automatic train stop, said means including a combined application and cut-off valve having connections with said brake valve and having means for venting said brake pipe through said double heading 75 cock if an attempt is made to defeat a train stop operation by closing said double heading cock. 80

3. In a train control system, a brake valve and electro-pneumatic means responsive to 85 wayside signals for automatically operating the equalizing piston of said brake valve to effect an automatic train stop, said means including an electrical device by which a signal preliminary to an automatic train stop operation may be acknowledged and the stop prevented, and a brake application valve associated with said brake valve and having means for cutting off all supply of air to said 90 brake valve upon an automatic train stop operation and having means for simultaneously opening a circuit to said acknowledging device whereby the automatic train stop operation, once initiated, cannot be prevented 95 by the engineman. 100

4. In a train control system, a main reservoir; a brake valve having pneumatic connections with said reservoir and with a train brake pipe, and having an equalizing piston for reducing pressure in said brake pipe; electro-pneumatic means, responsive to wayside currents to effect an automatic train stop, including a magnet valve, an application valve apart from said brake valve, and a pneumatic circuit controller connected to said main reservoir through said application valve, said application valve having means for cutting off all supply of air from the main reservoir to said brake valve, having means for causing the operation of the brake valve 110 to effect a train stop, and having means for venting the circuit controller. 115

5. In a train control system, a brake valve, a brake pipe, a double heading cock interposed between said brake pipe and brake valve, electro-pneumatic means responsive to 120 wayside currents for automatically operating said brake valve to effect an automatic train stop, said means including an application valve associated with said brake valve and having means for cutting off all supply of air to said brake valve upon an automatic train stop, and a connection from said double heading cock to said application valve where- 125 by upon an attempt to defeat a train stop 130

operation by closing said double heading cock, the brake pipe will be vented through said application valve.

In testimony whereof, we have hereunto signed our names at Altoona, Pennsylvania, this 2d day of March, 1929.

ROBERT C. BURNS.
